UNITED STATES PATENT OFFICE.

WILLIAM O. ISAACSON, OF CHICAGO, ILLINOIS.

ANCHOR.

Application filed March 15, 1926. Serial No. 94,905.

This invention relates to anchors for fastening bucks and the like into place, and with regard to certain more specific features to means for permanently holding objects 5 to concrete and like surfaces.

Among the several objects of the invention may be noted the provision of means adapted to be readily fastened to the object to be held, the provision of means for driving a 10 nail or the like therethrough into concrete or other hard and brittle material without loosing a grip or hold because of chipping away of said material, the provision of a compact and simple device which may be shipped flat, 15 and one which is exceedingly easy to manufacture and put into use. Other objects will be in part obvious and in part pointed out hereinafter.

The invention accordingly comprises the 20 elements and combination of elements, features of construction, and arrangements of parts which will be exemplified in the structure hereinafter described, and the scope of the application of which will be indicated 25 in the following claims.

In the accompanying drawings in which are illustrated two of various possible embodiments of the invention,

Fig. 1 is a perspective view of the anchor 30 showing it in flat position;

Fig. 2 is a view similar to Fig. 1 showing a tongue of the anchor struck up;

Fig. 3 is a side elevation of a portion of a door buck in use, showing parts broken away 35 and the anchor applied thereto;

Fig. 4 is a horizontal section taken on line 4-4 of Fig. 3;

Fig. 5 is a vertical section of a concrete 40 floor and wall showing the application of the anchor to a carpet strip and to a ground;

Fig. 6 is a perspective view of a modified 45 form of anchor; and

Fig. 7 is a longitudinal section of Fig. 2 showing in dotted lines, the flattened position 50 of the anchor.

Similar reference characters indicate corresponding parts throughout the several views of the drawings.

Referring now more particularly to Fig. 1, 55 there is illustrated at numeral 1 an elongated flattened extension sheet of an anchor A, at one end of which is formed a conical crater-like raised portion 3 having an opening 5

at the apex thereof and a hollow portion thereunder. The portion 1 is crimped laterally along a line 7, on the outside of which is formed a tongue or fastener 9.

The piece thus far described comprises a stamping, properly cut, formed and crimped, all of which operations may be completed at 60 a single operation of a die. Fig. 7 indicates that the under side of the conical portion 3 forms a hollow or depression 10 to be used for purposes hereinafter to be described. The cone 3 is formed and drawn from material 65 which previously formed a flat portion of the sheet 1.

Fig. 1, which shows the tongue flat, illustrates the preferred shipping form of the device, although it may be shipped in the 70 form illustrated in Fig. 2. In Fig. 2 the tongue 9 has been turned upwardly at an angle of approximately ninety degrees to the portion 1. This bending may be done during the process of manufacture, if desired, or by means of a hammer blow or the like at the time that the anchor is put into use. The material comprising the anchor is 75 of sufficient thickness to provide ample stiffness to the cone 3 and the bent tongue 9, and it may be made proof against corrosion by choosing the proper material or by coating the material such as by performing a tinning, galvanizing or the like operation thereon.

In Fig. 6 is illustrated a modified form of tongue 9 having a plurality of tines 11. Two tines 11 are illustrated in Fig. 6, but their number may be increased indefinitely. The modified anchor B shown in Fig. 6 is manufactured in a manner analogous to the way in which the previously described form A is manufactured.

The application of the anchors for holding a door buck in place is illustrated in Figs. 3 and 4. Each wooden leg 13 of the buck is grooved at a point 15 for receiving and engaging the bricks, stones, tile, concrete or the like of a wall 17. The buck is set up before the wall is set. Before the buck is set it has a predetermined number of anchors driven upwardly into the lower ends of the legs thereof (only one leg is shown in the drawings). The anchors are applied by driving the tongues 9 with a hammer or the like upwardly into the lower ends of the legs 13.

The conical portions 3 are left to extend outwardly to the sides of the legs 13. One or more anchors may be applied to a leg 13.

After the anchors are applied to the buck, 5 as described, then the buck is set into place and a hardened nail 19 is driven downwardly into the opening 5 of the cone 3. A hammer is again employed. If it is assumed that the buck is erected on a concrete, tile, 10 brick or like floor, then the nail, as it is driven down, has at first its usual tendency to chip and break the hard floor material. This chipping action ordinarily results in a 15 complete loss of wedging action of the nail, with a consequent loss of holding power. With the present invention, the first chips engendered are retained in the recess 9 instead of flying away and as the nail is further driven are packed into said recess there- 20 by preventing further chipping. As the final blows are given to seat the head on the cone 3, the cone is somewhat, though not completely flattened, and the chipped material therebeneath is tightly compressed. 25 The result is an improved holding power with the present anchor. The hardened nail serves the purpose of piercing the hard floor material without bending. The opening 5 is made slightly smaller than the nail 30 so that as the nail is driven it is frictionally prevented from rebounding from the hard surface. The conical portion also supports the nail while it is being driven so that it need not be manually held. Increased 35 safety is thus provided for the fingers of an operator.

It is to be understood that, if desired, the 40 bucks or the like may be applied to wooden or other relatively soft floors. A hardened or other nail may be used. This anchor also provides an improved result when the floor or the like is not hard and apt to chip, because aside from the anchor's chip-retaining qualities, the strained conical portion 45 acts as a compression brace after nailing.

After the buck is in place, that is anchored, then placement of the wall 17 may be accomplished. If it is a brick or like wall 50 the lower corner unit thereof is chipped to clear the head of the nail 19. The chipped corner is then grouted properly.

Fig. 5 illustrates another group of applications of the anchor. At numeral 21 is 55 shown a carpet strip adapted to be laid around the edges of a room having a concrete or like hard floor F. The wooden strip 21 has a series of anchors applied thereto before laying. The conical portions 3 extend from the strip. The anchors are then 60 fastened, after the strip is laid in place, by driving hardened nails into the cones 3. The described improved holding qualities are gained.

After the strips 21 are laid a filler 23 is 65 applied to the floor up to the level of the

strips. The carpet 25 is laid over the filler 23 and strips 21, and held to the latter by quarter-round pieces 27 or the like.

Before laying the carpet and quarter-round strips 27, the wall W of the room is 70 usually surfaced with plaster P. Just before plastering is done, a ground strip 29 should be applied at the upper portion of the wall W for fastening picture molding and the like. This ground strip 29 may be 75 fastened to the wall by means of the present improved anchor. Anchors are driven into the back of the ground strip 29 before it is applied. These anchors preferably 80 protrude their conical portions from each side of the strip, that is, if the strip does not abut the ceiling.

In finishing a room the carpet strip and ground strip are usually laid at the same time. Plastering is then accomplished. It 85 may be seen that this present type of anchor may be effectively used for various attachment purposes in and about building construction where hard or soft surfaces are to have fastenings made therewith. Much 90 time is economized, because heretofore it was necessary to drill holes for applying expanding holders for each fastening to be made in hard material. With the present invention a multiplicity of operations are 95 condensed into a few. Better alignment may be accomplished because no drilled holes need be met by a plurality of fasteners.

In view of the above, it will be seen that the several objects of the invention are 100 achieved and other advantageous results attained.

As many changes could be made in carrying out the above constructions without departing from the scope of the invention, it is 105 intended that all matter contained in the above description or shown in the accompanying drawings shall be interpreted as 110 illustrative and not in a limiting sense.

I claim:

1. An anchor of the class described comprising an extension portion, means for fastening said portion to a member to be anchored at one end of said portion comprising at least one fastener adapted to enter 115 said member, means for fastening said portion to another member at the other end of said portion comprising at least one raised portion having a hollow portion thereunder, and means for permitting the passage of at 120 least one fastener through said hollow raised portion, said fastener comprising a hardened member adapted to pierce hard material.

2. An anchor of the class described comprising means for fastening to a device to be anchored, at least one raised portion therewith hollow on its under side, and means for permitting the driving of a fastener through said raised portion, said fas- 125 130

tener comprising a hardened member adapted to enter hard material and having a head adapted to depress the said raised portion as said fastener finally enters the material.

5 3. An anchor of the class described comprising an extension portion, a fastener at one end thereof comprising a struck up tongue, means for fastening the anchor at the other end thereof comprising a raised portion, a hollow portion thereunder, a passage through the raised portion adapted to receive a fastener to pass through the hollow portion.

10 4. An anchor of the class described comprising an extension portion, a fastener at one end thereof comprising a struck up tongue, means for fastening the anchor at the other end thereof, comprising a raised portion, a hollow portion thereunder, a passage through the raised portion adapted to receive a fastener to pass through the hollow portion, and a head on the fastener adapted to depress the raised portion when said fastener is driven home.

15 5. An anchor of the class described comprising an extension portion, a fastener at one end thereof comprising a struck up tongue, means for fastening the anchor at the other end thereof comprising a raised portion, a hollow portion thereunder, a passage through the raised portion adapted to receive a fastener to pass through the hollow portion, the hollow portion being adapted to entrap and compress chips engendered by driving the fastener.

tion, and a head on the nail adapted to depress the conical portion when the nail is driven home.

6. An anchor of the class described comprising an extension portion, a fastener at one end thereof comprising a struck up tongue, means for fastening the anchor at the other end thereof comprising a raised conical portion, a hollow portion thereunder, a central passage through the raised conical portion adapted to receive a hardened nail to pass through the hollow portion, and a head on the nail adapted to depress the conical portion when the nail is driven home, said conical portion being adapted to entrap and compress chips engendered by driving the nail.

7. An anchor of the class described comprising an extension portion, a fastener at one end thereof comprising a struck up tongue, means for fastening the anchor at the other end thereof comprising a raised portion, a hollow portion thereunder, a passage through the raised portion adapted to receive a fastener to pass through the hollow portion, the hollow portion being adapted to entrap and compress chips engendered by driving the fastener.

In testimony whereof, I have signed my name to this specification this 9th day of March, 1926.

WILLIAM O. ISAACSON.
